UNITED STATES PATENT OFFICE.

WILLIAM A. HASSERIES, OF EVANSVILLE, INDIANA.

AWNING.

1,151,266.

Specification of Letters Patent. Patented Aug. 24, 1915.

Application filed August 4, 1913. Serial No. 732,879.

To all whom it may concern:

Be it known that I, WILLIAM A. HASSERIES, a citizen of the United States, residing at Evansville, county of Vanderburgh, 5 and State of Indiana, have invented certain new and useful Improvements in Awnings, of which the following is a specification.

My invention relates to awnings which are secured to and rolled upon a roller to be attached to the top of the window casing.

The object of this improvement is to provide a simple and effective device of the character mentioned, which when unrolled will have its upper portion parallel with 15 and close to the window, and its lower portion extending outwardly from said window. It will be noticed that the awning need not be positioned as above described but can be so operated as to give the entire awning an 20 outwardly extending shape.

A further object of my invention is to provide an awning having the above characteristics, which will obviate entirely the use of guide rods and the like.

I attain these objects by the arrangement 25 of parts illustrated in the accompanying drawings in which,

Figure 1 is a view, in perspective, of a window equipped with an awning embodying my invention; Fig. 2 is a central vertical section of the same; Fig. 3 is an enlarged fragmental section of the same, but showing the awning rolled up, and, Fig. 4 is a perspective of the bracket.

The preferred form of construction as 30 illustrated in the accompanying drawings comprises an awning fabric 4 wound upon a spring roller 5 which is mounted in bearings 6. The fabric 4 winds and unwinds 40 from the outside of the roller, that is, the part farthest away from the window. The lower end of the fabric 4 is secured in any desirable manner to the lower edge of a substantially U shaped frame 7 which frame 45

7 is secured at its end portions in suitable brackets 8. My improved bracket 8 is provided with a closed portion 8' upon its upper part as shown in Fig. 4. This closed portion 8' will not extend out far enough to 50 prevent frame 7 from closing up snugly against the window frame 10, but will extend out far enough to be engaged upon its under side by the upper part of the frame 7 which is back of the hinge, and thus limit 55 the downward movement of the frame 7; and at the same time relieve the awning

fabric 4 from the weight of said frame. Supports 9 may also be secured to the window casing 10 in suitable position to engage the frame 7. The part 8' and the supports 60 9, or either of them, obviate entirely the necessity for guide rods and the like as now used in most other awnings of the same general character as is mine. Formed in the central portion of the web 4 is a transversely 65 extending eye 11 in which is inserted a rib 12 provided to give the awning fabric lateral stiffness. In the middle of the rib 12 a cord or its equivalent 13 is suitably attached and extends downwardly and is adjustably 70 secured to a stop member 14 in the lower portion of the casing 10. The cord 13 in conjunction with the rib 12 normally holds the portion of the awning fabric 4 between the rib 12 and the roller 5 in vertical position, thereby maintaining this portion of the awning close to the window casing when the awning is unrolled. The cord 13 further provides a means for raising and lowering 75 the awning.

The awning may be maintained at any height from its unrolled position and may be maintained in several other positions as for instance that shown by dotted lines 15 in Fig. 1.

When the awning is rolled up as illustrated in Fig. 3, the rib 12 will wind up with the fabric 4 on the roller 5 and the cord 13 will of course, do the same.

While I have illustrated and described the 90 preferred form of construction for carrying my invention into effect, this is capable of variation and modification without departing from the spirit of the invention; I, therefore do not wish to be limited to the 95 precise details of construction set forth, but desire to avail myself of variations and modifications as come within the scope of the appended claims, and especially desire to avail myself of any means which support 100 my awning frame in the position shown in Fig. 1.

Having described my invention, what I claim as new and desire to secure by Letters Patent is;

1. The combination with a substantially U-shaped awning frame of a fabric, the upper end of said fabric being fastened to a spring roller, the lower end thereof being fastened to the front portion of the said 110 frame, said roller being adapted to be fastened to a support, a pair of brackets fas-

tened to said support at a point below said roller and the inner ends of said frame being pivotally related to said brackets, a bracing element extending transversely of said fabric 5 and approximately the center thereof, a cord with one end affixed to said bracing element at approximately the center thereof and passing downwardly through a retaining element and slidably related thereto, 10 said retaining element being affixed to said support at a point below said brackets.

2. The combination with a substantially U-shaped awning frame of a fabric, the upper end of said fabric being fastened to 15 a spring roller, the lower end thereof being fastened to the front portion of said frame, said roller being adapted to be fastened to a support, a pair of brackets fastened to 20 said support at a point below said roller and the inner ends of said frame being piv-

otally related to said brackets, a bracing element extending transversely of said fabric at approximately the center thereof, a cord with one end affixed to said bracing element at approximately the center thereof and 25 passing downwardly through a retaining element and slidably related thereto, said retaining element being affixed to said support at a point below said brackets, said brackets having two forwardly extending 30 ears, said ears having a bridge across a portion and to the rear of their upper edges.

In testimony whereof, I hereunto affix my signature in the presence of two wit- 35 nesses.

WILLIAM A. HASSERIES.
